UNITED STATES PATENT OFFICE.

FRANK C. WIDMANN, OF CLEVELAND, OHIO.

COMBINED SALT AND PEPPER SHAKER.

Application filed May 16, 1923. Serial No. 639,293.

To all whom it may concern:

Be it known that I, FRANK C. WIDMANN, a citizen of the United States, residing at Cleveland, in the county of Cuyahoga and

5 State of Ohio, have invented a certain new and useful Improvement in a Combined Salt and Pepper Shaker, of which the following is a full, clear, and exact description, reference being had to the accompanying drawings.

10 This invention relates to improvements in a combined salt and pepper shaker of the type set forth in my co-pending application Serial No. 630,235 filed April 6, 1923.

15 Briefly, the combined shaker common to that application and the present one comprises a container having a partition therein which divides it into two compartments, a perforated closure disposed across the top of the 20 container, and a selective device cooperating with the closure to permit the flow of one condiment to the exclusion of the other from the container.

The objects of this invention are to simplify and cheapen the construction set forth 25 in the above application and to obtain a selecting device which may be more readily put in place and is less liable to inadvertent removal.

30 The means for carrying out the above objects will be fully set forth in the following description, which pertains to the accompanying drawings. The essential features of this invention will be summarized in the 35 claims.

In the drawings, Fig. 1 is a plan of a combined salt and pepper shaker showing the normal position of the selective device for permitting the flow of salt therefrom; Fig. 40 2 is another plan showing the device in position to permit the flow of pepper; Fig. 3 is a vertical section taken on the correspondingly numbered line in Fig. 1; Fig. 4 is an elevation of a part of the container showing the manner in which the closure may 45 be removed from the container; Fig. 5 is a side elevation of a portion of container shown in Fig. 4 with the closure attached to the container; and Fig. 6 is an elevation of 50 the selecting device removed from the container.

I have illustrated my invention as used on a combined salt and pepper shaker 10 which is provided with a partition 11, for 55 dividing the container into two compartments as at 12 and 13. A perforated closure

14 extends across the top of the container and carries a slide 15 which may be arranged to permit the flow of the contents from one compartment to the exclusion of that in the 60 other compartment. The slide is normally held in the position shown in Fig. 1 and is arranged to be moved to the position shown in Fig. 2 by a manually operable lever 16 which may be pivoted at 17 on a bracket 18. 65 This bracket preferably forms an extension of the closure.

To attach the closure to the container, I prefer to employ a pair of cooperating shoulders on the closure and container and 70 a latch for retaining the shoulders in engagement. As illustrated, the shoulders on the container are formed on opposite sides thereof as at 20 and 21 by the upper wall of a recess in the side of the container. A 75 shoulder 22 on the closure cooperates with the shoulder 20, while a shoulder 23 on the latch 24 cooperates with the shoulder 21.

The latch 24 is preferably mounted on the same pivotal connection 17 as the lever 16 80 and is normally urged into locking position by a spring 25. The latch preferably comprises a bifurcated member, the sides of which extend outside the bracket 18 and the intermediate portion of which forms the 85 shoulder 23. Suitable ears 26 may project laterally from the latch beyond the edges of the lever 16 to permit the operator to release the latch from engagement with the shoulder 21 and thereby to remove the closure from 90 the container.

Assuming that a closure and selectively operated device embodying my invention are placed upon a container and locked thereto, then the normal position of the slide is that 95 illustrated in Fig. 1. In this position, the slots 30 in the slide are in registration with openings 31 over the compartment 12 while the slots 32 are out of registration with openings 33 over the compartment 13. Thus 100 when the container is inverted and shaken, the contents flow from the compartment 12, while the contents of the compartment 13 are retained in place.

When it is desired to use the contents in 105 the compartment 13 to the exclusion of the contents of the compartment 12, the user presses the lever 16 and thereby moves the slide 15 to the position shown in Fig. 2. This 110 movement closes the openings 31 and uncovers the openings 33 and thus permits the flow of condiment from the compartment 13.

As soon as the pressure on the lever is released, the spring 25 pushes the lever outwardly, thus causing the slide to assume its former position.

- 5 When it is desired to remove the closure for purposes of filling the compartments, the user releases the shoulder 23 from engagement with the shoulder 21 by pulling outwardly on the ears 26 against the tension of the spring 25. When the latch is thus released, the closure and slide may be removed as a unit from the container. To replace the closure the reverse procedure is followed, that is, the shoulder 22 is placed in engagement with the cooperating shoulder 20, whereupon the opposite side of the closure is pressed downwardly until the latch 24 is brought into engagement with the shoulder 21.
- 20 From the foregoing description, it will be seen that my invention provides a device which when adapted to a combined salt and pepper shaker enables one container to be used for both condiments and permits the use of one condiment to the exclusion of the other. Moreover, the invention provides a device which may be readily locked to the container and easily removed therefrom for filling or cleansing purposes, but is not liable to be inadvertently removed in the normal use of the article.

I claim:—

1. In combination a container having spaced notches therein, a closure for said container, a slide movable relatively to the closure and carried thereby, an inwardly extending shoulder rigid with the closure and engaging one of said notches, a bracket carried by the closure, a pair of levers 35 mounted on a common pivot on said bracket, one of said levers being adapted to engage the slide for moving it with relation to the closure and the other of said levers being adapted to engage the other of said notches 40 for clamping the closure to the container.

2. In combination, a container, a closure therefor, a slide movable relatively to the closure, a lever pivotally mounted on the closure and operatively connected to the 45 slide, a latch pivotally mounted on the closure and adapted to engage the container for locking the closure thereto, said latch having a laterally extending portion projecting beyond the side of the lever, whereby the 50 lever may be operated independently of the latch and the latch may be operated independently of the lever.

3. In combination, a container, a perforated closure therefor, a perforated slide 55 carried by the closure, a lever operatively connected to the slide and having the fulcrum therefor on the closure, a pivoted latch

having the fulcrum thereof on the closure and on the same pivot as same lever, said latch comprising a U-shaped member having 65 the sides extending outside the lever and having the intermediate portion extending transversely of the container and cooperating with a shoulder thereon for locking the closure to said container and means for urging the lever and latch in opposite directions.

4. In combination, a container, a perforated closure therefor, a perforated slide carried by the closure, cooperating shoulders on the closure and container respectively, a lever operatively connected to the slide and having the fulcrum therefor on the closure, a pivoted latch having the same fulcrum as the lever, said latch comprising 80 a U-shaped member having the sides extending outside the lever and having the intermediate portion extending transversely of the container and cooperating with one of said shoulders for locking the closure to said 85 container and a spring for urging the lever and latch in opposite directions.

5. In combination, a container, a closure therefor, a slide carried by the closure, said container having oppositely spaced shoulders thereon, said closure having an inwardly extending shoulder cooperating with one of the container shoulders, a bracket on the closure, an operating lever and a latch lever both mounted on the same fulcrum in said bracket, the operating lever being operatively connected to the slide and the latch levers being adapted to cooperate with the other one of the container shoulders for locking the closure thereto, said latch lever having 100 an ear extending beyond the side edge of the operating lever for enabling the latch lever to be disengaged from the container.

6. In combination, a container, a closure therefor, a slide carried by the closure, said container having oppositely spaced recesses therein, said closure having an inwardly extending shoulder cooperating with one of said recesses, a bracket on the closure, an operating lever and a latch lever mounted 110 on the bracket, the former lever being operatively connected to the slide and the latch lever being adapted to cooperate with the other recess in the container for locking the closure thereto, said latch lever having a pair of laterally extending portions for enabling it to be disengaged from the container, and spring means for urging the latch lever toward the container and the operating lever away from the container.

In testimony whereof, I hereunto affix my signature.

FRANK C. WIDMANN.
